Des. 31

Samuel H. Ranson, Albany, New York.
Letters Patent (Design) No. 31, dated July 16th 1845.

The schedule referred to in these Letters Patent and my
new part of the same

To all whom it may concern: Be it known that I
Samuel H. Ranson of Albany in the County of Albany and
State of New York have invented or produced a new ornamental
design for a stone, and I do hereby declare that the following
is a full, clear and exact description thereof, reference being had
to the accompanying drawings on aking part of this specification:
Fig. 1. represents a stone constructed after my design. Fig. 2. repre-
sents an enlarged view of the side of the stone and Fig. 3
a view of one half the front, the other portion being of course
symmetrical with this. The ornament upon the side doors
is a base of flowers; those upon the front fire doors b. b. and
the oven c are in the style of Louis XIV. The borders consist
of a continuation of the figures d. d. e. e. f. f. &

What I claim as my invention and desire to secure
by letters patent, is, the combination and arrangement of or-
namental figures herein described forming an ornamental
design for a stone
